UNITED STATES PATENT OFFICE.

THOMAS E. ROBINSON, OF TULSA, OKLAHOMA.

CASING CLAMP FOR OIL WELLS.

1,402,092.

Specification of Letters Patent. Patented Jan. 3, 1922.

Application filed February 28, 1921. Serial No. 448,322.

To all whom it may concern:

Be it known that I, THOMAS E. ROBINSON, a citizen of the United States, residing at Tulsa, in the county of Tulsa and State of Oklahoma, have invented certain new and useful Improvements in a Casing Clamp for Oil Wells, of which the following is a specification.

My invention relates to oil well drilling appliances, and particularly to a clamp for holding and setting a well casing. In oil well drilling, the method in use at the present time, comprises drilling a large bore, of approximately ten inch diameter at the surface, a sufficient depth to reach the bed of shale or stone. When this has been accomplished a casing approximating eight and a quarter inches in diameter, is "set" within the bore to rest at the bottom on the shale bed. The casing consists of joints of pipe averaging twenty two feet in length and it is necessary that this casing be cut to the exact length required. Generally the proper apparatus for cutting the casing, and threading the upper section, is not available at the well and considerable delay is caused while the casing is being measured, cut and threaded to engage the flange at the well surface.

After the casing has been cut and positioned it frequently becomes necessary to drill the original bore farther below the casing. This necessitates raising the casing and passing a reamer therethrough, which expands below the bottom of the casing to the diameter of the original bore. This process is called underreaming. Owing to the length of the casing sections the lower end of the casing must be raised a considerable distance and as the earth at this point is generally loose, it often happens that it caves in upon the underreamer, hindering, and often preventing operation thereof. When the casing is finally reset a new upper section must be cut and threaded.

The primary object of my invention is to provide a casing clamp arranged at the well surface, which will eliminate the necessity of cutting and threading the upper section of the casing and which eliminates the waste of time, labor and material due to the method heretofore employed.

A further object is the provision of a simple and efficient clamp of the character described, for permitting adjustment and underreaming of the casing.

Another object is the provision of such a clamp for accurate holding and setting of the casing.

With these and other objects in view, which will be apparent from the description, my invention resides in the novel construction, combination, and arrangement of parts, hereinafter described and claimed, and illustrated in the accompanying drawings, of which:

Fig. 1, is a vertical section of the upper end of a well and casing with the clamp in position.

Fig. 2, a top plan view of the clamp, 70

Fig. 3, an elevation of an element of the clamp,

Fig. 4, a fragmentary section on line 4—4 of Fig. 3, and

Fig. 5, a section on line 5—5 of Fig. 3. 75

In the preferred form, I provide a short supporting pipe section 1 of large diameter, which is driven in at the top of the well around the bore after same has been drilled in the usual manner. The well casing 2 is 80 then lowered into the bore in the usual manner, and held at any desired elevation by means of clamping members 3 coacting with the outer supporting pipe 1 and the casing 2, being disposed therebetween as 85 shown in Fig. 1.

I prefer to use three of these clamping members, but any desired number may be employed. As they are identical in construction, detailed description of one will 90 suffice for all. An individual clamp member comprises an arcuate outer member in the form of a plate 4, of a length to extend well into the pipe 1, and provided with a lateral exterior flange 5 to engage over the 95 upper end of pipe 1 for support therein. Below the flange, the body of the plate is considerably reduced in thickness forming a shoulder 6, and from this point the inner face of the plate inclines outwardly to the bottom, forming a wedge face. Coacting with the plate 4 is an oppositely wedge shaped inner member in the form of a generally similar plate 7, slidably secured on the plate 4 by means of a detachable, dove-tailed lug 8 disposed in a longitudinal dove-tailed slot 9 provided in the plate 4, whereby the members are detachably secured in 100 movable relation.

The inner face of the member 7 is provided with serrations 10 to 105 permit of positive frictional gripping engagement with the casing 2. 110

In operation, the pipe 1 and casing 2 having been positioned, the clamps 3 are inserted between the pipe and casing in radial spaced relation, whereupon the serrated faces of the members 7 will engage the casing to rigidly clamp same in position owing to the wedge formation of the clamp plates. When the casing is raised, the plates 7 will ride up on the plates 4 to allow free upward movement of the casing, but any downward movement thereof will be arrested by reason of the wedge action of the clamps.

It will be apparent that with this construction, when it is desired to underream the casing, it may be lifted only a few inches thereby eliminating the probability of the earth caving in upon the underreamer. It is obvious that the casing can be set at any desired point, thereby eliminating the cutting of the upper section, and the provision of the supporting pipe does away with the threading of the upper section and the flange now employed.

While I have shown and described certain materials and details which enter into the construction and operation of my invention, I desire it to be understood that I do not limit myself to these, but that any such may be used as will fall within the scope of the invention as claimed.

I claim:

1. A casing clamp for oil wells, comprising a member serrated for engagement with a well casing, a wedge member adapted for insertion within a support, said members being secured together in relatively slidable relation.

2. In a casing clamp for oil wells, a support, a wedge plate, means on said plate adapted to engage said support for suspension of the plate therein and a casing en-

gaging wedge plate, said plates being permanently connected in slidable relation.

3. In a casing clamp for oil wells, a supporting pipe section, a wedge plate adapted to be inserted therein, a flange on said plate, adapted to engage over an end of said pipe section for suspension of said plate, a wedge plate adapted to engage a well casing, and detachably arranged permanent connection between said plates arranged for relative movement of the plates.

4. In a casing clamp for oil wells, a supporting stationary pipe section, an arcuate longitudinally wedge shaped plate suspended therein, a flange on said plate adapted to engage one end of said pipe section, a member adapted to engage a well casing and slidably disposed on said plate, and means for permanent attaching connection between said plate and member.

5. A casing clamp for oil wells comprising a stationary tubular support, an arcuate plate, a member on said plate adapted to engage loosely over an end of said support to suspend said plate therein, said plate having a longitudinal dovetailed slot, a wedge plate, casing engaging means on one face thereof, a lug on the opposite face thereof and disposed in said slot for slidable permanent attaching connection between the plates, within said support.

6. A casing clamp for oil wells, comprising a pair of oppositely wedge shaped abutting members, permanent attaching connection between said members arranged for slidable relation of the members, supporting means on one of said members, and casing engaging means on the other of said members.

In testimony whereof I affix my signature.

THOMAS E. ROBINSON.
